Cortland, N. Y., a corporation of New York

Application March 11, 1936, Serial No. 68,166

15 Claims.

(Cl. 96—11)

Our invention relates to improvements in the art of braiding machinery and provides for efficient novel control appurtenances of a character that greatly facilitates the economical manufacture of tapered fish lines and the like braided cords on a rapid productive scale at the minimum of labor costs.

The present innovations are primarily directed to the fabrication in one length of a so-called double tapered fish line. Such braided line product may be provided with oppositely disposed, level terminal regions of relatively small diametral size while an intermediate braided belly region is gradually built up to a considerably larger size.

While one or more core strands may be utilized to enlarge such belly region, it is herein preferred to work without resort to such internal braid reenforcement in order to maintain a snugly braided yet soft and pliable fish line that shall be intrinsically free from faults when subjected to arduous service. In such instance, the number of incorporated line strands remains the same throughout the length of a tapered line and the linear unit weight of the component bobbin threads is progressively changed in stepwise fashion until the desired medial belly size has been attained. Thereupon, the braiding process is reversed and stepped down until the original terminal level size is reached.

The fabrication of such a tapered line usually involves careful and laborious supervision to insure the production of a high grade product since the conventional braiding machine needs to be stopped manually each time a comparatively short length of line has been laid. Some one of the plural carrier bobbins is then changed by the attendant to allow of tying in a somewhat heavier or lighter strand, and this operation must be successively repeated in rotation until all such bobbins have been changed to a different thread that shall be appropriate to make up the required run of line size. Without special equipment, such frequent stopping and starting of the braider calls for constant personal attendance and thus materially adds labor charges over that needed when braiding a uniformly level line.

Our improvements provide certain automatic means for cutting down on the need for such intrinsically high supervision cost by allowing the operator to effectively handle a much greater number of braiding machines without sacrifice in quality on part of the resulting tapered product. The pattern control means herein provided, serves to positively stop the machine after

a definitely measured length component of tapered line has been braided and this in turn, gives a cue to the attendant calling for a required bobbin thread change without depending upon the operator's personal judgment. Consequently, 5 the operator is not obliged to keep a close watch in order not to overrun the proper component length of completed line.

Furthermore, when fabricating a tapered line without inserted core strands, the heft of the 10 braided strand must be correspondingly enlarged at regular intervals to form a taper of predetermined maximum size. The rotative rate of the take-up draw spool or capstan governs the number of picks or pitch spacing between the laid braider strands. Hence when using a fixed rate of carrier travel, the speed of the draw spool should be proportionately changed, otherwise the strands become too loosely or too tightly braided for an inherently pliable fish line that is intended to handle well when cast by an expert fisherman. 15 The relative speed adjustments in take-up rate on part of the draw spool has generally been accomplished by manually making the necessary gear ratio change in the drive mechanism to compensate for the required pick variation. Such 20 further supervision by the attendant is likely to render the operator's hands dirty and thereby soil the finished braid. By virtue of our improved braider accessories, the speed of the draw spool is gradually rather than abruptly advanced 25 or retarded with respect to the carrier travel to suit requirements.

The object of our improvements is to overcome 30 the cited manufacturing deficiencies so as to enhance the product uniformity and otherwise reduce factory costs as applied to high quality fish lines and analogous plaited cords of the character indicated.

Reference is had to the accompanying three 35 sheets of drawings which are illustrative of a preferred assembly of our invention, and in which drawings:

Fig. 1 represents a perspective front view of a 40 conventional braider machine unit equipped with our improved devices, and Fig. 2 is an elevational 45 side view thereof which reveals certain appurtenances attached to such machine.

Fig. 3 shows a plan view of our braider as seen 50 from above along line 3—3 of Fig. 1, while Figs. 4 and 5 depict certain enlarged details associated therewith.

Fig. 6 illustrates in exaggerated diametral scale, one kind of tapered product or article which 55 our machine is intended to fabricate, and Fig. 7

diagrammatically indicates the corresponding positions of a cam and its roller.

Fig. 8 schematically shows a modification in that a conventional speed change gear box may be substituted for our preferred frictional face plate drive.

Referring more specifically to the drawings, our improvements may be applied to a well known type of braider as furnished by the New England Butt Company of Providence, R. I., and others. This usually comprises a stationary transverse platen 10 having a pair of complementary transverse grooves such as 11 cut therethrough to constitute an endless serpentine path that guides a series of bobbin carriers 12 in the conventional manner. In the present instance, eight or more plaited strands such as 13 may be used. In addition, this braider may also be provided with one or more core strand bobbins (not shown) as in the Hodgson and Reynolds Patent #1,537,445 of May 12, 1925. Since the means for imparting movement to the respective carriers do not constitute the essential subject matter of our improvements, it is sufficient for present purposes, to point out that such well known type of braider is generally equipped with an actuated stop mechanism which admits of automatically shutting down the braider should any one of the processed strands become ruptured. This same stop mechanism is herein utilized and made to cooperate with a dislike pattern adapted to automatically cease operations whenever sufficient tapered line length has been fabricated to require a change in strand size.

Said conventional machine equipment may further comprise a spring actuated knockoff plate or equivalent device 14 of arcuate shape of which one end region is fulcrumed to the stationary platen at 15. The opposite plate end region is usually provided with a protruding portion 16 which lies close to but is made to normally clear the travel path of the several carriers. As will be understood, each carrier also includes a drop weight or the like arranged to actuate the knockoff plate radially outward about its fulcrum upon rupture of any one tensioned braider strand.

Such machine may be power driven through the pulley 17. The gear interconnected bobbins may be meshed with an intermediate spur gear 18 rotatably mounted upon the upright drive shaft 19. A suitable clutch 20 may be disposed beneath said spur gear and the pulley made to drive the bobbins therethrough. The laterally shiftable knockoff plate may be provided with a notch 21 disposed to engage a depending link 22 having a latching head thereon and which head is releasably retained by said plate whenever the manipulative lever 23 is raised to engage the pulley clutch. When the plate 14 is swung radially outward by interference with a carrier portion, the gear clutch 20 will be automatically released and thereby bring about a stoppage in the braiding operations. The described clutch control may be termed "stop mechanism".

Elevated above the platen is a superstructure including a pair of stanchions such as 24 which rotatably mount the overhead cross shaft 25. Said cross shaft is usually provided with suitable braid take-up mechanism or draw spool devices collectively designated as 26. This capstanlike metering means for the laid braid may be positively actuated in unison with the rotation of the braider bobbins by the use of a train of gears that commonly includes a pair of change gears. In conventional practice, the relative number of

teeth in these complementary replacement gears are from time to time changed manually in step-wise fashion to modify the pick of the laid strand when braiding a tapered fish line. On the other hand, our braid take-up mechanism provides automatic control means for gradually changing the rate of rotation of the draw spool in a commensurate relation to the thread size requirements of the tapered braid while the carriers remain running at a fixed speed.

The forward end of our cross shaft 25 may be equipped with a flat driven disc or face plate 30 that frictionally cooperates in quadrature with a toothless drive pinion 31, as shown in Fig. 1. Such pinion may be operatively mounted upon an auxiliary spindle 32 of which the axis is directed radially toward the center of the cross shaft. This spindle is axially shiftable and slidably embraced by a splined rotatable sleeve 33 that is retained against endwise movement. The lower end of said sleeve may be equipped with a bevel gear 34 which is driven from the horizontal countershaft 35. The opposite end of the last named shaft may be provided with a gear 36 that meshes with the worm 37 mounted upon the upright drive shaft 19. This arrangement is such that the pinion 31 is rotated in unison with the drive pulley 17 under command of the clutch 20 and which spindle is vertically shiftable in its surrounding sleeve to modify the rotative speed of the draw spool while the braider remains operative.

That is to say, a lifting of the spindle brings about an accelerated speed rate in the disc 30 whereas a spindle drop carries the pinion 31 radially away from the axis of the cross shaft 25 and correspondingly slows up the relative disc speed. Any suitable means may be employed in raising or lowering the spindle to suit the prevailing pick requirements. In the present instance, such adjustable speed control means reside in the use of a heart shaped cam 38 mounted upon the transverse lay shaft 39. This cam may be provided with vertically guided roller or other follower means 40 adapted to transmit the vertical component of roller movement beneath the bottom of the spindle through the use of a suitable follower linkage such as 41 or the like. One end of said lay shaft may be provided with a reduction gear 42 of which the worm may be sprocket driven at 43 by the chain 44 that is in turn actuated from the rear end of the cross shaft 25. As a result, said lay shaft will be rotated at an extremely slow rate in relation to the braider carriers so as to make but one whole revolution for the completion of a single tapered fish line. The indented cam profile may be changed within wide limits and is shaped to respond to the character of taper and its predetermined disposition along a finished fish line length.

The opposite end of the lay shaft carries a specimen pattern which in the present disclosure comprises one or a series of control discs 45 that are rotated in unison with the slow moving cam 38. In order to obviate the need for an excessively large single disc diameter, we preferably resort to the use of a compact stack of smaller discs which may be laterally separated by suitable spacer means to provide for a groove between each pair of next adjacent discs. A peripheral portion of each such disc is given a symmetrical notched formation as at 46, 46', etc. (see Figs. 4 and 5) with respective notches of the several discs disposed angularly about a com-

mon axis in staggered succession for reasons that will appear presently. Such notches may or may not be evenly spaced, since such angular relation is dependent upon the characteristics of the completed article. One end of the guided tongue member 47 may be pivotally attached at 48 by retractile means to the knockoff plate 14, as indicated. The other tongue end may be provided with an acute pawl 49 adapted to enter into some one of the disc notches. An actuating spring 50 normally thrusts said pawl radially inward toward the axis of the rotatable lay shaft 39.

The toe width of said pawl is kept proportional to the disc thickness and this toe may be laterally shifted by a manipulative knob 51 about the tongue pivot 48 to selectively cooperate with the successive next adjacent notches afforded by the several control discs 45A, 45B, etc. Suitable retaining means such as the cited grooves between the discs may be provided to hold the pawl in aligned registry with the thickness of any one rotating disc.

The effective length of said tongue is such that whenever the pawl rides upon a disc perimeter, the latchable head on the link 22 will remain engaged with the plate notch 21 and thus hold the clutch 20 in operative engagement. However, when the control disc has advanced sufficiently to allow the beveled pawl to drop into one of such aligned disc notches, this will release the link head and automatically throw the gear clutch out of engagement to shut down the braider. Said notches are preferably so spaced as to properly time such shut down and thereby automatically signal the operator when to make a required bobbin thread change. Thereupon, the braider is restarted until the reaching of a next contiguous notch calls for another thread change.

Because our draw spool and the control disc 45 are positively interconnected to rotate in unison, the spacing between successive disc notches serves to definitely meter a linear length of completed braid. Such a machine may be additionally equipped with the usual takeup reel 52, also level winder mechanism 53, guide holder and the like conventional accessories that need not be defined in detail.

Attention is now directed to Fig. 6 which shows a double tapered fish line product in which the bellied portion is disposed symmetrically between the line ends. As actually manufactured, an exemplification thereof is being marketed in a standardized continuous length of about 90 ft. The relatively short trailing line end or component L2 may be kept at the same diametral size D1 and weight that is given to the forward link or leader component L6. Between these sections there may be braided an interposed weight-ed belly region having a uniform or level diametral size D2 for a considerable length L4. In actual dimensions, D1 usually corresponds approximately to $\frac{3}{2}$ " in size while D2 may run several times as large. The respective belly ends are gradually tapered in the component lengths L3 and L5 until their adjacent smaller line sizes are reached. The fabrication may be carried on as a continuous process as represented in dotted outline, when the completed line is cut to the overall length L1.

When starting to braid the smaller sized components L2 or L6 thereof, the pawl 49 will be disposed midway between the oppositely disposed disc notches 46 and 46' of the disc 45C as in Figs. 4 and 5. At this instant, the roller 40 will ride

upon the bottom of the depressed cam profile in the Fig. 7 manner. Both Figs. 4 and 7 denote the particular cam portion that responds to the Fig. 6 component lengths. Assuming both the cam 38 and the discs 45 to be rotating clockwise on the common lay shaft 39 corresponding to a limited angle designated L2, then the roller 40 remains at a fixed radial distance from the axis of the shaft 39. In the meantime, the notch 46 will be advancing toward the pawl 49 and when ultimately reached, the machine will be automatically shut down by release of the drive clutch 20. This first step completes the level line component L2.

The operator thereupon increases the strand size on one carrier and restarts operations by lifting the lever 23 and thereby relatching the head of the link 22 into engagement with the knockoff plate, as described. Prior thereto, the retractile pawl 49 will have been lifted out of its notch and shifted laterally into alignment with the contiguous disc 45B so as to ride upon the periphery thereof and thus again hold the clutch 20 in operative engagement. The next adjacent notch of the disc 45B will then similarly advance toward the readjusted pawl until the machine is again brought to rest for another thread change. A subsequent raising of the pawl 49 radially away from the lay shaft axis, causes the clutch to be thrown into engagement and allows the braiding operations to proceed. Resort to multiple discs obviates the placing of an excessively large number of notches on any one disc and still provides for the desired fine gradation corresponding to something like 6" of completed linear taper length between thread changes.

While the taper L3 is being braided, the roller 40 will gradually and automatically creep up toward the outermost perimetric profile of the cam 38 in accordance with some exemplar and thereby correspondingly increase the speed of the draw spool which in turn properly compensates for the needed larger pick of the heavier belly forming strands. When the roller rides upon the truly circular portion of the cam, the pick will be maintained constant throughout the length L4. During the same period, the disc 45 is kept free from notches and hence allows the braider to complete the belly component without machine shut down. As intimated, when working on the converging taper L5, all operations are reversed until finally the smaller level component L6 is completed and the article as a whole fabricated with the minimum of expenditure of time and labor.

It is also within the scope of our invention to resort to but one disc having a single notch thereon so as to automatically bring the machine to rest after braiding a predetermined line length. Such pattern would then be correspondingly speeded up to have such single notch rotate through one whole revolution instead of the restricted angular distance designated L2 in Fig. 4. Means might readily be provided to render such single disc notch inoperative while fabricating the uniformly large article diameter D2 of Fig. 6 so as not to interrupt the braiding thereof.

Also instead of resorting to our cam actuated frictional disc drive, similar results as applied to certain purposes may be had by the use of a speed change gear box 67 of the kind depicted in Fig. 8. It is common practice to drive the cross shaft 25 through a set of replaceable interposed spur gears such as 60 and 61 represented in dotted outline. The relative number of teeth in the re-

spective meshed gears may be altered to suit draw spool pick requirements when fabricating a tapered fish line or the like in a built-up fashion. As a substitute for the change gears 60 and 61, 5 said box may be equipped with one or more pairs of mated spur gears such as 63 and 64, also 65 and 66. By manually actuating the control lever 68, the differently sized gears 63 and 65 may be laterally shifted into mesh with either the gears 64 10 or 66. The rotative speed of the cross shaft 25 is thereby correspondingly modified with respect to the rate of carrier travel. Such handle manipulation still leaves our pattern disc intact and operative to automatically bring the braider to 15 rest after a definite length of tapered line has been laid. When such gear box is provided with a plurality of similarly controlled gear sets, any desired range of speed change increments, may be obtained.

20 It will be observed that with our improvements, the tapered length component is gradually stepped up in diametral size and in proper pick spacing until a larger level is reached. Such procedure makes for a high grade fish line that is 25 uniformly built up and capable of being rapidly produced at a comparatively low first cost. It is emphasized that since our lay shaft 39 is positively geared to the cross feed shaft 25 to run in unison, the control disc 45 cannot get out of synchronism 30 when fixing the location of the tapered line component in the finished article, irrespective of any relative speed change that may be effected by the cam 38 or the gear box 67. In addition, means are provided for simultaneously varying the rotative rate of the draw spool together with such pattern disc in a definite relation to the carrier speed. Our braider machine provides for a gradual rather than a markedly abrupt change in 35 taper and its pick compensating means obviates the need for frequent servicing of the conventional change gears 60 and 61.

Such automatic devices not only improve the quality and uniformity of product at the minimum of material wastage, but also fortify against 45 the element of human frailty by requiring all thread changes to be made at regular intervals when braiding a tapered line. The preceding disclosure will it is believed, make apparent to those skilled in this art, the resulting advantages 50 afforded by our braider innovations. While the present specification has primarily been directed to the fabrication of tapered fish line, this is not intended to imply a corresponding restriction in the wider application of our machine improvements and it is to be understood that various 55 changes in such illustrative embodiment may be resorted to, all without departing from the spirit and scope of our invention heretofore described and more particularly pointed out in the appended 60 claims.

We claim:

1. In a braider machine, means for braiding strands of material and which means include a plurality of bobbin carriers, power driven means 65 for bodily rotating the carriers about a common axis, a centralized stop mechanism commanding the power driven means and serving to bring the carriers to rest, movably mounted pattern means also actuated by said power driven means and 70 which pattern while operative is continuously moved in unison with the carriers, said pattern being interconnected to control the stop mechanism and serving to automatically shut down the rotation of the carriers after a predetermined 75 length of braid has been laid, and means for auto-

matically changing the pick of such braid in a proportionate relation to the laid length thereof.

2. In a braider machine, means for braiding strands of material and which means include a plurality of bobbin carriers, power driven means 5 for bodily rotating the carriers about a common axis, a stop mechanism commanding the power driven means and serving to bring the carriers to rest, a rotatably mounted pattern disc, interconnecting gear means to rotate the disc in unison 10 with the carriers, said disc being operatively connected to actuate the stop mechanism and serving to automatically shut down carrier rotation after a predetermined length of braid has been laid, draw spool means serving to meter the predetermined 15 length of laid braid and which means are rotated axially in unison with the pattern disc, and means for progressively modifying the relative speed between said draw spool means and the pattern disc.

3. In a braider machine, means for braiding strands of material and which means include a plurality of bobbin carriers that are rotatably mounted to travel bodily upon a platen about a common axis, power driven means rotating 25 the carriers, a stop mechanism including knock-off plate means pivotally mounted upon the platen, a rotatably mounted pattern disc having spaced notches thereon and which disc is rotated in unison with the carriers, and shiftable 30 tongue means operatively disposed between the knockoff plate and the disc, one end region of said tongue means being provided with retractable pawl means adapted to engage a disc notch and thereby automatically actuate the stop mechanism.

4. In a braider machine, means for braiding strands of material and which means include a plurality of bobbin carriers that are rotatably mounted to travel bodily upon a platen about a 40 common axis, power driven means for rotating the carriers, a stop mechanism including knockoff plate means pivotally mounted upon the platen, pattern means comprising a stack of rotatably mounted control discs each having a plurality 45 of notches in the respective peripheries thereof and which disc notches are perimetricaly staggered relative to each other, means simultaneously rotating said discs, and a shiftably mounted tongue operatively disposed between the knockoff 50 plate and the respective discs, one end region of such tongue being provided with pawl means adapted to selectively enter any one of the disc notches.

5. In a braider machine, means for braiding 55 strands of material and which means include a plurality of bobbin carriers, power driven means for bodily rotating the carriers at a certain travel rate about a common axis, a stop mechanism commanding the power driven means and serving 60 to bring the carriers to rest, movably mounted pattern means actuated by said power driven means to move in unison with the carriers, said pattern being operatively connected to control the stop mechanism, rotatable draw spool means arranged to take up the laid braid, means rotating the draw spool from the power drive means, and means changing the speed rate of the draw spool 65 with respect to the aforesaid carrier travel rate.

6. In a braider machine, means for braiding 70 strands of material and which means include a plurality of bobbin carriers, power driven means for bodily rotating the carriers at a certain travel rate about a common axis, a stop mechanism commanding the power driven means and serving 75

- to bring the carriers to rest, a notched pattern rotatably mounted contiguous to and arranged to control said stop mechanism and which pattern is operatively connected to rotate in unison 5 with the carriers, an overhead cross shaft rotatably mounted above the carriers, draw spool means carried by the cross shaft, a driven face plate erected upon the cross shaft, a toothless pinion arranged to frictionally engage the face 10 plate and which pinion is shiftable radially with respect to the shaft axis, means driving said pinion in unison with the carriers, and means for shifting the pinion to change the pick rate of the laid braid.
- 15 7. In a braider machine, means for braiding strands of material and which means include a plurality of bobbin carriers, power driven means for rotating the carriers to run at a certain travel rate about a common axis, a stop mechanism commanding the power driven means and serving to bring the carriers to rest, movably mounted pattern means actuated by said power driven means to move in unison with the carriers, said pattern being operatively connected to control 20 said mechanism and serving to intermittently stop the carriers, rotatable draw spool means for taking up the laid braid and which means are rotated from the power driven means, and means for automatically modifying the rate of 25 spool take up during one such carrier running period.
- 30 8. In a braider machine, means for braiding strands of material and which means include a plurality of bobbin carriers, power driven means for bodily rotating the carriers at a certain travel rate about a common axis, rotatable draw spool means arranged to take up the delivered braid, and means driving the draw spool in unison with 35 said carriers, said means comprising adjustable control devices for automatically modifying the rate of spool take up with respect to the aforesaid carrier travel rate in a proportionate relation to the length of the delivered braid.
- 40 9. In a braider machine, means for braiding strands of material and which means include a plurality of bobbin carriers, power driven means for bodily rotating the carriers about a common axis, overhead cross shaft means extending over 45 said carriers, draw spool means mounted upon the cross shaft and arranged to take up the laid braid, frictional drive means for rotating the cross shaft from the power driven means, said frictional drive means comprising an axially retained sleeve member that is positively actuated to rotate in 50 unison with the carriers and has a splined axially shiftable spindle mounted therethrough and which spindle carries a toothless pinion at one end thereof, and means for adjustably shifting 55 said spindle while its sleeve is being rotated.
- 55 10. In a braider machine, means for braiding strands of material and which means include a plurality of bobbin carriers, power driven means for bodily rotating the carriers at a certain travel rate about a common axis, rotatably mounted cross shaft means operatively connected to run 60 in unison with the carriers, draw spool means mounted upon said cross shaft, lay shaft means, means driving the lay shaft from the cross shaft, and control means simultaneously changing the speed rate of the lay and cross shafts with respect 65 to the aforesaid carrier travel rate.
- 65 11. In a braider machine, means for braiding strands of material and which means include a plurality of bobbin carriers, power driven means for bodily rotating the carriers at a certain travel 70 rate.
- 75 rate about a common axis, rotatably mounted cross shaft means operatively connected to run in unison with the carriers, draw spool means mounted upon said cross shaft, lay shaft means, means driving the lay shaft from the cross shaft, a stop mechanism commanding the power driven means and serving to bring the carriers to rest, pattern means mounted upon the lay shaft and which pattern is operatively connected by actuated tongue means to control the stop mechanism, and change gear means simultaneously modifying the speed rate of the lay and cross shafts with respect to the aforesaid carrier travel rate.
- 15 12. In a braider machine, means for braiding strands of material and which means include a plurality of bobbin carriers, power driven means for bodily rotating the carriers at a certain travel rate about a common axis, rotatably mounted cross shaft means operatively connected to run 20 in unison with the carriers, lay shaft means, drive means for running said lay shaft from the cross shaft at a relatively slower speed, a stop mechanism commanding the power driven means to bring the carriers to rest, pattern means mounted 25 upon the lay shaft and which pattern is arranged to actuate said stop mechanism, and adjustable control means serving to change the rate of the cross shaft speed with respect to the aforesaid carrier travel rate.
- 30 13. A machine for laying tapered braid and which machine comprises a plurality of bobbin carriers, power driven means for bodily rotating the carriers about a common axis, rotatably mounted cross shaft means operatively connected 35 to run in unison with the carriers, draw spool means for said cross shaft arranged to take up and meter the laid braid, a stop mechanism commanding the power driven means to bring the braiding machine to rest, a rotatably mounted specimen pattern that is also operatively connected to run in unison with the carriers, said pattern being arranged to actuate the stop mechanism and which pattern during one revolution thereof serves to repeatedly stop the braiding 40 machine in a substantially definite relation to a linear length component of laid strand as metered by the draw spool.
- 45 14. In a braider machine, means for braiding strands of material and which means include a plurality of bobbin carriers, power driven means for bodily rotating the carriers about a common axis, a stop mechanism including knockoff plate means that commands the power driven means and brings the carriers to rest, rotatably mounted 50 pattern means provided with a plurality of notches that are perimetricaly spaced apart about the axis of rotation thereof, tongue means operatively interconnecting the pattern with said knockoff plate and which tongue is equipped with 55 pawl means adapted to enter one of the pattern notches and thereby actuate the stop mechanism, draw spool means arranged to meter the laid braid, and means for rotating the draw spool and pattern in unison with the carriers, one of the 60 aforesaid notches being thereby advanced toward the pawl means to time the linear length component of laid braid that the draw spool is permitted to meter prior to bringing the carriers to rest.
- 65 15. In a machine for laying tapered braid and which machine comprises means for braiding strands of material including a plurality of bobbin carriers, power driven means for bodily rotating the carriers at a certain rate of travel 70
- 75

about a common axis, rotatable cross shaft means, draw spool means mounted upon the cross shaft and arranged to take up the laid braid, and manipulative gear box means provided with a series of mated change gears that are operatively mounted to selectively drive the cross shaft therethrough from the power driven means at

different speeds with respect to the carrier travel and thereby progressively modify the pick of the laid braid in different component length regions of the completed product.

LAWRENCE F. BROWN,
PAUL A. ALLEN.
